CLAIM

The ornamental design for retractable scissors, as shown and described.

DESCRIPTION

FIG. 1 is a perspective view of the retractable scissors showing our new design;

FIG. 2 is another perspective view of the retractable scissors showing our new design with the scissors retracted;

FIG. 3 is a front elevational view thereof;

FIG. 4 is a left side elevational view thereof;

FIG. 5 is a top plan view thereof;

FIG. 6 is a rear elevational view thereof;

FIG. 7 is a right side elevational view thereof; and

FIG. 8 is a bottom plan view thereof.
